UNITED STATES PATENT OFFICE.

WILLIAM M. BOWLES, OF SAPULPA, OKLAHOMA, ASSIGNOR TO INTERNATIONAL CRUDE
OIL STORAGE COMPANY, INC., OF SAPULPA, OKLAHOMA.

ELECTRIC SIGNAL.

1,275,179.

Specification of Letters Patent.

Patented Aug. 6, 1918.

Original application filed December 31, 1915, Serial No. 69,609. Divided and this application filed November 21, 1916. Serial No. 132,669.

To all whom it may concern:

Be it known that I, WILLIAM M. BOWLES, a citizen of the United States, residing at Sapulpa, in the county of Creek and State 5 of Oklahoma, have invented certain new and useful Improvements in Electric Signals, of which the following is a specification.

This invention relates to signal devices for use in connection with the safety vents 10 for crude oil storage tanks, and has as its object the provision of means for giving both an audible and visible signal in the event of the vent pipe being struck by lightning and the safety valve becoming 15 closed, so that the attendant may be apprised of the closing of the said safety valve within the pipe and may restore the device to its normal condition.

In the accompanying drawings:—

20 Figure 1 is a perspective view of the vent pipe embodying the invention;

Fig. 2 is a vertical longitudinal sectional view through the said pipe, the parts being shown in normal positions;

25 Fig. 3 is a view similar to Fig. 2 illustrating the positions of the parts after the pipe has been struck by lightning.

In the drawings, the numeral 1 indicates in general a crude oil storage tank which 30 tank, of course, may be of any desired form and capacity and the numeral 2 indicates a closure for the filling opening in the top of the tank. Leading from the top of the tank to the vent pipe which is to be hereinafter 35 specifically described and which is located at any desired distance from the tank is a pipe line 3 which serves to carry off the gases rising from the oil within the tank and to convey these gases to the said vent 40 pipe.

The vent pipe mentioned above is preferably mounted at its lower end upon a foundation 4 of concrete or any other suitable material and this pipe is preferably built 45 up from a number of sections connected in a manner to be presently explained, the lowermost one of these sections being indicated by the numeral 5 and being in communication at its lower end with an opening 6 in 50 the foundation 4, this opening providing for drainage of the vent pipe both as concerns the collection of rain water therein and the collection of any condensed gaseous vapors. A pipe section 7 is mounted upon the pipe 55 section 5 and the said sections 5 and 7 are

preferably provided with flanges bolted or otherwise secured together, as indicated at 8. A pipe section 9 is mounted upon the pipe section 7 and another pipe section 10 is mounted upon the section 9. In one side, 60 the pipe section 7 is formed with an opening 11 surrounded by a valve seat 12 disposed at an angle with relation to the axis of the pipe, as clearly shown in Figs. 2 and 3 of the drawings.

The numeral 21 indicates a valve which is pivotally mounted as at 22 at the upper side of the valve seat 12 within the pipe section 7 and this valve is normally supported in open position in a manner which will now 70 be described and is adapted, when released, to fall by gravity to a position against the seat 12 and thereby close the opening 11 which establishes communication between the pipe line 3 and the interior of the vent 75 pipe. In order that access may be had to the valve 21 a hand hole 23 is provided in the pipe section 7 opposite the said valve seat 12 and is closed by a suitable cover 24. Secured at their lower ends to the pipe section 10 and projecting upwardly in spaced relation above the said pipe section are brackets 25 provided at their upper ends with binding posts 26 to which are secured the ends of a fuse wire 27, this wire extending between the said upper ends of the brackets 25 and, consequently diametrically above the upper end of the pipe section 10. A wire or other suitable flexible or semi-flexible element 28 is connected at its upper 80 end to the fuse wire 27 and at its lower end to the valve 21 and serves to support the said valve normally in open position, as above stated. In order that the pipe sections 7 and 9 may be insulated from each 85 other and in order that the pipe sections 9 and 10 may be insulated from each other, insulating gaskets 29 are interposed between the connected ends of the said sections respectively and the bolts 30 which secure the 90 flanges at the said ends of the sections together are surrounded by insulating sleeves 31. To insure against the gases issuing from the vent pipe being ignited in the lower portion of the pipe a foraminous screen 32 is interposed between the ends of the pipe sections 9 and 10 and a similar screen 33 is arranged at the upper end of the section 10, the wire 28 passing through openings in the 100 said screens. It will now be understood that 105

110

should lightning strike the vent pipe the charge would, since the pipe sections 9 and 10 are insulated with respect to each other as well as with respect to the ground be directed to the fuse wire 27 which, by being grounded through the wire 28 and valve 21, would be fused. The valve would, therefore, be allowed to drop by gravity to closed position. Therefore, even should the gases 10 at the upper end of the pipe section 10 be ignited, the flame would not reach to the gases of the lower portion of the vent pipe nor to the pipe line 3. Should the valve 21 be closed in the above manner and should 15 the attendant fail to properly restore the same to open position the walls of the tank 1 will not be subjected to external pressure in the event that oil is pumped from the tank, inasmuch as when a partial vacuum is 20 created within the tank in the pumping operation, the valve 17 will be lifted from its seat and the air will enter the pipe line 3 and be conducted to the tank.

In order that both an audible and a visible 25 signal may be given to indicate the closing of the valve 21, means are provided which will now be described. Mounted for rocking movement, as at 34, in the brackets 25 is a shaft 35 provided at one end with a head 30 36 to which is connected the inner end of a rod 37 carrying at its outer end a semaphore 38. The other end of the shaft 35 is provided with an arm 39 carrying a weight 40 held at adjustment thereon by means of 35 a set screw 41. An arm 42 is secured to the shaft 35 between the brackets 25 and is provided with a hooked end 43 which engages with the fuse wire 27. In the normal position of the parts the arm 39 is inclined upwardly and at an angle to the vertical and consequently the weight 40 exerts a normal 40 tendency to swing this arm in a downward direction. Also in the normal position of the parts the semaphore 37 extends in a general downward direction but it will be understood that in event of fusing of the wire 45 45 27 the shaft 35 will no longer be restrained against rotary movement and will be rotated through the downward swinging movement of the arm 39, the semaphore being at the same time swung upwardly to about the 50 position shown in Fig. 3 of the drawings in which position it will serve as a visible signal to the attendant that the valve 21 is in closed position.

The numeral 44 indicates a bracket preferably located at the lower end of that one of the brackets 25 next adjacent which the arm 39 is located and this bracket supports a contact plate 45 insulated from the bracket as indicated at 46. A conductor wire 47 is connected to the contact plate 45 and to one pole of a battery 48 and a wire 49 leads from the other pole of the battery 55 60 65 to a bell or annunciator indicated at 50.

A wire 51 is connected electrically with the other one of the brackets 25 or some other portion of the device which is not insulated from the arm 39 and is connected also with the bell 50. Thus when the wire 27 is fused and the arm 39 swings downwardly the weight 40 will strike against the contact plate 45 and complete the circuit through the bell or annunciator 50, giving an audible signal that the valve 21 is closed.

70
75

The present application is a division of my copending application for patent on safety vents for crude oil storage tanks, filed December 31, 1915, Serial No. 69,609.

Having thus described the invention, what is claimed as new is:

1. In a device of the class described, a vent pipe, a valve within the pipe having a normal tendency toward movement to closed position, a fusible element, means supporting the said element and engaged with the extremities thereof, connection between the said element and the valve normally holding the valve in open position, the said connection being engaged with the intermediate portion of the said element, a rotatable element, means carried by the said rotatable element and projecting in front of the said fusible element for normally holding the rotatable element against rotation, and a signal adapted to be rendered active upon movement of the said movable element.

2. In a device of the class described, a vent pipe, a valve within the pipe having a normal tendency toward movement to closed position, a fusible element supported above the pipe to extend diametrically thereof, connection between the said element and the valve normally holding the valve in open position, a shaft, means carried by the shaft and engaging the intermediate portion of said element for normally restraining the said shaft, and a signal arranged for actuation by the said shaft.

3. In a device of the class described, a vent pipe, a valve within the pipe having a normal tendency toward movement to closed position, a fusible element supported above the pipe to extend diametrically thereof, connection between the said element and the valve normally holding the valve in open position, a rotary shaft, an arm carried by the shaft and normally projecting in front of the said fusible element and constituting a means for restraining the shaft from rotation, and a signal arranged for operation by the said shaft.

4. In a device of the class described, a vent pipe, a valve within the pipe having a normal tendency toward movement to closed position, a fusible element, connection between the said element and the valve normally holding the valve in open position, a rotary shaft normally restrained from movement by the said fusible element, an

electric signal circuit including a contact insulated from the pipe and shaft, an arm upon the shaft, and means adjustable upon the said arm and in the said circuit, the shaft being movable to engage the said means with the contact for closing the signal circuit through the shaft upon the release of the said shaft by fusing of the said element.

5. In a device of the character described, a vent pipe, spaced arms supported thereby, a fusible element supported between the said arms, a valve within the pipe having a normal tendency toward movement to closed position, connection between the said element and the valve normally holding the valve in open position, a shaft mounted upon the said arms, means carried by the shaft and projecting in front of the said 20 fusible element for normally restraining the shaft against rotation, and a signal arranged for actuation by the said shaft.
6. In a device of the character described, a vent pipe, spaced arms upstanding from the upper extremity of the said pipe, a fusible element extending diametrically of the pipe between the said arms and detachably engaged at its extremities with the upper

terminals of the arms, a valve within the pipe having a normal tendency toward movement to closed position, a connection between the said element and the valve normally holding the valve in open position, a shaft rotatable upon the said arm, means carried by the shaft and projecting in front of the said fusible element for normally restraining the shaft against rotation, and a signal arranged for actuation by the said shaft.

7. In a device of the character described, a vent pipe, a valve within the pipe having a normal tendency toward closed position, a fusible element, connection between the said element and the valve normally holding the valve in open position, a rotatable shaft normally restrained from movement by the said fusible element, an electric signal circuit including a contact insulated from the pipe and shaft, and a weighted element associated with the said shaft and included in the circuit, the said weighted element normally tending to rotate the shaft for movement to engage with the said contact.

In testimony whereof I affix my signature.

WILLIAM M. BOWLES. [L. S.]
